(57) **CLAIM**

The ornamental appearance of a microwave disinfection slotted radiator, as shown.

DESCRIPTION

FIG. 1 is a top perspective elevational view thereof of a microwave disinfection slotted radiator, showing my new design;

FIG. 2 is a right side elevational view thereof;

FIG. 3 is a right side elevational view thereof;

FIG. 4 is a top plan view thereof;

FIG. 5 is a bottom plan view thereof;

FIG. 6 is an end plan view thereof; and,

FIG. 7 is an opposing end plan view thereof.
